(57) CLAIM

The ornamental design for a grill pan, as shown and described.

DESCRIPTION

FIG. 1 is a top perspective view of a grill pan, showing our new design.

FIG. 2 is a top plan view thereof.

FIG. 3 is a bottom plan view thereof.

FIG. 4 is a front elevation view thereof; and,

FIG. 5 is a side elevation view thereof.

The broken lines in the drawings depict portions of the grill pan that form no part of the claimed design.

1 Claim, 4 Drawing Sheets
